(57) **CLAIM**

The ornamental design for a vibrating electromechanical device, as shown and described.

DESCRIPTION

FIG. 1 is a bottom, front and left perspective view of a vibrating electromechanical device showing our new design; FIG. 2 is a top, front and right perspective view thereof; FIG. 3 is a right elevational view thereof; FIG. 4 is a left elevational view thereof; FIG. 5 is a bottom plan view thereof; FIG. 6 is a top plan view thereof; FIG. 7 is a back elevational view thereof; and, FIG. 8 is a front elevational view thereof. The broken lines in the figures illustrate unclaimed environment and form no part of the claimed design.
